UNITED STATES PATENT OFFICE.

WILLIAM WHELAN, OF ST. JOSEPH, MISSOURI.

ELECTRICAL WATER-HEATER.

1,319,315.

Specification of Letters Patent.

Patented Oct. 21, 1919.

Application filed June 27, 1918. Serial No. 242,148.

To all whom it may concern:

Be it known that I, WILLIAM WHELAN, a citizen of the United States, residing in the city of St. Joseph and State of Missouri, have invented new and useful Improvements in Electrical Water-Heaters, of which the following is a specification, reference being had to the accompanying drawings.

This invention pertains to electrical heating devices and to devices of this character especially adapted for heating water or other liquids, and it has for its object the production of an apparatus for this purpose embodying the fewest possible parts, and 15 with same assembled in a simple, practical and efficient form.

With these objects in view, attention is called to the accompanying drawings, wherein—

20 Figure 1 is a perspective of my heater as disposed in a water container;

Fig. 2, a side elevation;

Fig. 3 is a vertical sectional view of the same electrical heating elements assembled 25 in a tank or cylindrical form of water container rather than the container shown in Fig. 1.

Fig. 4 is a plan view of the top portion;

Fig. 5 is a horizontal sectional view taken 30 on the line A—B in Fig. 2, and showing the disposition of the outer and inner cylinders and asbestos wick;

Fig. 6 is a detail showing the method of attaching the insulated handle to the apparatus, and including the overlapping brackets for engagement with the top of the water container;

Fig. 7 is a modification showing a simple 40 method of bending the conductor terminals so as to overlap the water container and sustain the apparatus in place;

Fig. 8 is a modification showing a flat 45 form of structure for the heater, including method of bolting the heating plates and asbestos wick together;

Fig. 9 is a detail showing the structure and formation of the heating plates;

Fig. 10 is a detail showing a method of 50 insulating the bolts and nuts from the clamping members.

Referring more particularly to the drawings, my apparatus, in its preferred construction, is made up of two heating cylinders as 1 and 2 of unequal diameters, so 55 that the heating cylinder 1 will set inside of the heating cylinder 2. These heating

cylinders are both perforated with a plurality of holes as shown at 3 and 4. A cylindrical asbestos wick 5 is disposed between the cylinders 1 and 2, and projects, as shown 60 at 6 and 7, at its upper and lower ends beyond the ends of the heating cylinders 1 and 2. Suitable electrical conductors as 8 and 9 are joined to the heating cylinders 1 and 2, and lead therefrom upwardly through 65 the top bar 10, ending in the terminal screws 11 and 12, and being insulated in passage through the top bar 10 by any suitable means. The top bar 10 is provided with projecting brackets 13 and 14 adapted to 70 set over the edge of any water container 17, and so sustain the apparatus in working position. An insulated handle 15 is provided to facilitate the handling of the apparatus. Wire conductors extend from the 75 terminals 11 and 12, and are joined in circuit to any electrical source as 16.

In the modification shown in Fig. 7, the conductors 8 and 9 are bent at their upper portions as shown at 18 and 19. In the 80 modification shown in Fig. 8, a flat form of structure is shown. The heating plates 20 and 21 are made flat and between them is imposed the flat asbestos wick 22, these elements being clamped together in flat 85 form by means of the clamps 23 and 24 bolted together at their ends. The clamps 23 and 24 are to be properly insulated so that the electrical current will pass through 90 the water rather than through the clamps. 90

In operation, the container 17 is partially filled with water, and the apparatus is set therein, being suspended from the top of the container by the brackets 13 and 14. The current is turned on, and water being only 95 a partial conductor of electricity, the resulting resistance to the current in passing between the heating cylinders 1 and 2 heats the surrounding water, and a circulating current is established in the water until the 100 entire body of water is heated.

The downwardly projecting end 7 of the wick 5 draws up the water from the container 17 to the last portion thereof. When the water is exhausted from the container 105 through evaporation or otherwise, the asbestos wick 5 becoming dry, and asbestos being a non-conductor of electricity, the current of electricity is automatically cut-off until a new supply of water is placed in the 110 container 17. The purpose of the perforations 3 and 4 is, of course, to afford the

water or liquid easy means of access to the asbestos wick 5.

Of course, the elements and apparatus as described may be elaborated into a complete hot water heating system for a house, or for generating steam to run an engine, or for other similar purposes, and while I have herein described a certain specific manner and method of constructing the elements 10 of my invention, it is understood that I may vary from the same in minor details, not departing from the spirit of my invention, so as best to construct a practical device for the purpose intended as defined in the appended claims.

What I claim to be new and patentable is:

1. An electrical water heater, comprising a source of electricity and in circuit therewith spaced, perforated heating plates; and 20 an absorbent, electrically non-conducting wick located between said plates.

2. An electrical water heater, comprising a source of electricity and in circuit therewith spaced, electrically conducting, perfo-

rated heating plates; and an absorbent, electrically non-conducting wick located between said plates. 25

3. An electrical water heater, comprising a source of electricity and in circuit therewith spaced, electrically conducting, perforated heating plates; and an absorbent, electrically non-conducting wick located between said plates, said wick projecting beyond said plates. 30

4. An electrical water heater, comprising a source of electricity and in circuit therewith electrically conducting, perforated metal cylinders, nested and spaced apart one within the other; an absorbent, electrically non-conducting wick located between said cylinders, said wick projecting beyond said cylinders; and insulated means for suspending the apparatus within a water container. 35 40

WILLIAM WHELAN.
